BOTTLE ADAPTER FOR BOTTLE FILLING MACHINES

Filed April 7, 1924

2 Sheets-Sheet 2

Inventor:
Arthur I. Risser
By Cheever & Cox Atty.

UNITED STATES PATENT OFFICE.

ARTHUR I. RISSE, OF CHICAGO, ILLINOIS, ASSIGNOR TO U. S. BOTTLE MACHINERY CO., OF CHICAGO, ILLINOIS, A CORPORATION OF ILLINOIS.

BOTTLE ADAPTER FOR BOTTLE-FILLING MACHINES.

Application filed April 7, 1924. Serial No. 704,560.

To all whom it may concern:

Be it known that I, ARTHUR I. RISSE, a citizen of the United States, residing at Chicago, in the county of Cook and State 5 of Illinois, have invented a certain new and useful Improvement in Bottle Adapters for Bottle-Filling Machines, of which the following is a specification.

This invention relates to machines more 10 or less common on the market in which a plurality of empty bottles are carried in upright position through the machine for filling and sometimes for sealing while in the machine and are thereafter delivered to 15 a point outside the machine.

As these machines are expensive, it is obviously necessary that they be adapted to handle bottles or other articles to be filled of different sizes and shapes, but the law 20 of operation of most of such machines is that the vertical axis of each bottle as it goes through the machine shall traverse a given, predetermined, horizontal line, commonly, not always, the arc of a circle.

The object of this invention is to provide 25 interchangeable bottle holders or retainers—one style for each kind or size of bottle which is to go through the machine—said retainers being interchangeably positionable

30 on the bottle carrier mechanism of the filling or capping machine which is in use whereby by selectively equipping the machine with the proper size of bottle holder or retainer, the mechanism will satisfactorily operate upon 35 the particularly type or shape of bottle which is to be handled.

The invention consists in mechanism capable of attaining the foregoing and other objects; which can be easily and cheaply 40 made; which is satisfactory in use and is not readily liable to get out of order. More particularly, the invention consists in numerous features and details of construction which will be hereafter more fully set forth 45 in the specification and claim.

Referring to the drawings in which like numerals designate the same parts throughout the several views:

Figure 1 is a side elevation, partly in section, of, for the purposes of this case, a conventional bottle filling machine equipped with the device of this invention.

Figure 2 is a plan view on the line 2—2 of Figure 1.

Figure 3 is a side and Figure 4 is a plan 55 view of a bottle holder for a cylindrical bottle.

Figures 5 and 6 are corresponding views 60 of an alternative bottle holder for a rectangular bottle.

Figure 7 is a perspective view of the parts shown in Figures 5 and 6, separated one from the other.

Figure 1 shows in side elevation what is, for the purposes of this application, a conventional bottle filling machine having a horizontal table 10 rotatable on the vertical axis of a shaft 12 through the agency of a conventionally power driven shaft 14 and gearing 16 and 18. This table carries at its center a liquid tank 20 surmounted by automatically operated siphon devices 22 movable from the position shown at the left hand side of Figure 1 to that shown at the right hand side. On the table and surrounding the tank 20 is an annular collar or wheel 24 having in its circumference a multiplicity of notches 26 adapted to be entered by bottles 28 which are carried into and out of the machine by a longitudinal conveyor 30, the bottles being guided to and from the table 10 and the wheel 24 by tracks 32 and 34, respectively. 70

When bottles are delivered by the track 32 onto the table 10, each bottle is engaged by a spring controlled roller 36, designed to press the particular passing bottle into an adjacent notch 26 in the wheel 24 so that the wheel and table will carry the successive bottles in a circle about the tank 10 85 and so accurately position them under the nozzles 37 of the siphon mechanisms 22 which are, as shown at the left of Fig. 1, raised as the bottle passes onto the table so that mechanism not shown in detail may, as the table continues to rotate, lower each successive siphon mechanism into its adjacent bottle or to the position shown at the right of Fig. 1, in which position the siphon mechanism fills the bottle. In order that 90 these siphon mechanisms 22 shall properly operate, it is absolutely essential that the bottles 28 be accurately centered in a circular path under the nozzle 37 which are to enter the bottle; viz.: in the arc of a circle about the axis of shaft 12. It is entirely apparent 95 that if the notches 26 and the wheel 24 were of one predetermined size, the central axis

of bottles of different diameters pressed into these notches by the roller 36 would not all lie in the same circular path about the center of shaft 12 and tank 20 and the result of this would be that the nozzles 37 would not enter the mouths of bottles 28 which were out of the circular path traversed by the siphon tubes and that bottles would be either broken or tipped over or something else unsatisfactory would happen to them because of this irregular positioning of bottles which were not of the exact size to fit the notches 26 in the wheel 24. In order to overcome this difficulty, the notches 26 are made substantially larger than the largest bottle which is to be handled by a given machine. In other words, in mechanism of this invention, the actual bottles 28 or 28^a do not at any time contact the walls of the notches 26, but the bottles are, on the other hand, placed in suitably formed recesses 38 or 40—as the case may be—formed in the faces of independent blocks 42 or 44, as the case may be, made with rear curved surfaces 46 which do in fact fit into the notches 26 on wheel 24. These adapter blocks are secured in predetermined positions in the notches 26 by any desired means, as for instance the overchanging lugs 48 carrying dowel pins 50, entering holes 52 provided for them in the upper surface of the wheel 24. These adapter blocks 42 or 44, as the case may be, are made of such a size that when a given block is placed in the notch 26 of the wheel 24, and the bottle for which that particular block is designed is placed in the face recess 38 or 40 of that block, the mouth opening of that bottle will travel in a circle directly under the nozzles 37 of the siphon mechanisms 22 with the result that

one such nozzle 37 can surely enter the bottle without damage thereto.

For purposes of illustrating, the cylindrical bottle 28 and rectangular bottle 28^a have been shown fitting in adapter blocks 42 especially designed to receive them but obviously, the configuration of the recesses 38 and 40 may be varied at will as the cross-sectional forms of the bottles to be handled by the machine may dictate.

Having thus described my invention, what I claim as new and desire to secure by Letters Patent is:

In mechanism of the class described, a bottle transporting member having a vertically extending notch, and an adapter member conforming to and detachably engageable in the notch, one of said members having an opening therein and the other having a dowel pin engageable in said opening to secure the members together with the side portions of the outer face of the adapter member in registry with the adjacent portions of the outer face of the bottle transporting member, said adapter member having a greater depth than the length of the dowel pin whereby the positioning of the lower end of the adapter member in the upper end of the notch with the side portions of its outer face in registry with the adjacent portions of the outer face of the bottle transporting member will aline said opening and dowel pin to effect certain engagement of the dowel pin in the opening by downward movement of the adapter member in the notch.

In witness whereof, I have hereunto subscribed my name

ARTHUR I. RISSE.
